CONCEALED HINGE

Emil B. G. Lefevre, Detroit, Mich.

Application March 6, 1935, Serial No. 9,634

3 Claims. (Cl. 16—163)

This invention relates to hinges capable of general application but particularly designed for use on automobile doors. It is well known that the upper and lower hinges on such doors are commonly spaced substantially apart and that the outer surfaces of the door and body are frequently curved or bulged outward between the hinges. It is accordingly necessary that the door be outwardly displaced as it begins to open, as the outwardly curved surfaces will otherwise contact.

A common manner of accomplishing this result is by providing outwardly extending hinges with their pivot-pins positioned substantially outside of the body and door surfaces. This construction, while effective, is ungainly, and the outwardly projecting hinge parts impair the beauty of the body design.

It is the general object of my present invention to provide an improved hinge which will project the door outward as it begins to open, and which will be entirely concealed when the door is closed.

A further object of the invention is to provide a concealed hinge which will firmly support a wide and heavy door without sagging or undesirable looseness in any position.

My invention further relates to arrangements and combinations of parts which will be herein-after described and more particularly pointed out in the appended claims.

A preferred form of the invention is shown in the drawing, in which

Fig. 1 is a sectional plan view of my improved hinge, together with portions of the associated door and body;

Fig. 2 is a view similar to Fig. 1 but showing a door and hinge in open position;

Fig. 3 is a front elevation of one of the hinge plates, looking in the direction of the arrow 3 in Fig. 1;

Fig. 4 is a similar view of the other hinge plate, looking in the direction of the arrow 4 in Fig. 1, and

Fig. 5 is a side elevation of one of the hinge links, looking in the direction of the arrow 5 in Fig. 1.

Referring to the drawing, I have shown a portion of a body B and a portion of a door D. The body B includes an outer metal casing or panel 10 having an inwardly offset corner portion or rabbet 11 which is thereafter extended inward to provide an edge portion 12.

The casing or panel 10 is cut away along the edge 12 inside the door opening and along a por-

tion of the corner or rabbet 11 at the points where hinges are to be applied, and at each of these points the body is provided with a reenforcing plate or hinge support 13 which is firmly secured in some convenient manner, as by spot-welding to some body part 15, such as pillar, panel reinforcement or bracket.

The reenforcing plate or hinge support 13 is provided with spaced elongated slots 14 for a purpose to be described. Any suitable interior 10 finish of leather, fibre, fabric or other material may be provided as indicated at 16.

The door D is similarly formed with an outer panel 20 having a projecting portion 21 flanged over the outwardly projecting edge portion 22 of 15 an inner casing or pillar 23. A portion 25 of the inner casing or pillar forms the edge of the door and connects the portions 22 and 23 previously described.

A reenforcing plate or hinge support 26 is preferably secured to the edge portion 25 by spot-welding or otherwise, and the reenforcing plate 26 has an offset portion 27 extending along the inner side of the door and having elongated spaced slots 28.

My improved hinge comprises hinge plates 30 and 31, hinge links 32 and 33, and a plurality of hinge-pins 34, 35, 36 and 37.

The hinge plate 30 is provided with countersunk holes 40 to receive screws 41 (Fig. 1) extending through the slots 14 in the reenforcing plate or hinge support 13 and threaded into a tapped plate 42 disposed at the rear of the reenforcing plate.

Reference to Fig. 2 will show that the screws 41 are readily accessible when the door is open, and that by loosening the screws 41 the hinge plate 30 may be adjusted transversely in the body B to cause the surfaces 10 and 20 of the body and door 40 to assume proper alignment.

Similarly, the hinge plate 31 is provided with countersunk holes 50 to receive screws 51 extending through the slots 28 in the reenforcing plate 26 and into a tapped plate 52. By loosening the screws 51, the door D may be adjusted widthwise relative to the body B, thus permitting convenient centering of the door in the door opening.

The hinge plate 30 is provided with an offset portion 60 from which extend upper and lower bearing members 61 and 62 which are provided with openings 63 and 64 for the hinge-pins 34 and 36 respectively.

The hinge plate 31 is provided with outwardly projecting bearing members 70 having openings

71 and 72 for the hinge-pins 35 and 37 respectively.

It will be noted that the hinge-pins 34 and 36 are abruptly and substantially offset from the 5 plane of the hinge-plate 30, while the hinge-pins 35 and 37 are only slightly out of alignment with the hinge-plate 31.

It will be noted also that the hinge-pins 35 and 37 are substantially further apart than the 10 hinge-pins 34 and 36 and that the link 33 is substantially longer than the link 32. The link 32 is also substantially arched to provide a recess 75 for the end of the link 33 when the door is open, as indicated in Fig. 2, in which position the link 15 32 and the end of the link 33 cooperate to form a stop.

A packing 77 is preferably secured under the projecting portion 21 of the door casing 20, to 20 form a windbreak as clearly shown in Figs. 1 and 2.

Hinges thus constructed possess very substantial and important advantages. Reference to Fig. 2 will show that the paths of swinging movement of the hinge-pins 35 and 37 do not at any point 25 intersect, and that they are always substantially spaced apart so that the overhanging weight of the door is in all positions firmly supported. The door movement is also such that the overhanging edge portion 21 has no motion toward the interior 30 of the car but remains substantially in one position during the initial opening movement of the door and thereafter moves rapidly outward to the position shown in Fig. 2.

The initial swinging movement of the door is 35 substantially about the point X (Fig. 1) near the end of the projecting portion 21 of the door and without perceptible movement of the door widthwise or in the direction of the arrow a in Fig. 1. Consequently, there is no binding of the door during 40 the initial opening movement.

After the swinging edge of the door has cleared the door casing, the point X follows substantially the curved line d to the position indicated in Fig. 2, the path of movement approximating a hyperbolic spiral. It will be apparent that the edge of the extension 21 at all times substantially clears 45 the outer casing 10 of the body, even in cases where the casing is substantially curved outward between the hinges.

Having thus described my invention and the advantages thereof, I do not wish to be limited to the details herein disclosed, otherwise than as set forth in the claims, but what I claim is:—

1. A concealed hinge comprising a first hinge 55 plate to be attached to a fixed member, a second hinge plate to be attached to a swinging member, and longer and shorter hinge links connecting spaced bearing points on one hinge plate to spaced bearing points on the other hinge plate, the bearing 60 points on said first hinge plate being disposed

in a line substantially inclined to the outer surface of said swinging member when said member is in closed position, the bearing points on said second hinge plate being in a line nearly parallel to said outer surface, and the bearing points on 5 said first hinge plate being substantially nearer together than the bearing points on said second hinge plate, the bearing point on said first hinge plate which is more remote from the securing portion of said first hinge plate and the bearing point on said second hinge plate which is nearer the securing portion of said second hinge plate being connected by the longer link.

2. A concealed hinge comprising a first hinge plate to be attached to a fixed member, a second 10 hinge plate to be attached to a swinging member, and longer and shorter hinge links connecting spaced bearing points on one hinge plate to spaced bearing points on the other hinge plate, the bearing points on said first hinge plate being 15 disposed in a line substantially inclined to the outer surface of said swinging member when said member is in closed position, the bearing points on said second hinge plate being in a line nearly parallel to said outer surface, and the bearing 20 points on said first hinge plate being substantially nearer together than the bearing points on said second hinge plate, the bearing point on said first hinge plate which is more remote from the securing portion of said first hinge plate and the bearing 25 point on said second hinge plate which is nearer the securing portion of said second hinge plate being connected by the longer link, and said 30 shorter link being arched to provide a recessed portion at one side thereof to receive one end of 35 said longer link, said recessed portion and said link end cooperating to form a stop when the 40 swinging member is in open position.

3. A concealed hinge comprising a first hinge plate to be attached to a fixed member, a second 45 hinge plate to be attached to a swinging member, and longer and shorter hinge links connecting spaced bearing points on one hinge plate to spaced bearing points on the other hinge plate, said first plate having a securing portion extending transversely of the outer surface of said fixed member, and said second plate having a securing portion extending substantially parallel to said outer surface, and means to attach said securing 50 portions to associated parts of said fixed and movable members, said attaching means comprising bolts extending through aligned openings in said securing portions and associated parts and certain of said openings being elongated, whereby each of said plates may be adjusted relative to its supporting structure in the plane of its securing portion and may be firmly secured in selected adjusted position.
